UNITED STATES PATENT OFFICE

JOSEPH B. CLAY, OF CEDAR FALLS, IOWA, ASSIGNOR TO CLAY EQUIPMENT CORPORATION, OF CEDAR FALLS, IOWA

GATE LATCHING DEVICE

Application filed April 16, 1931. Serial No. 530,615.

My invention relates to improvements in gate latching devices, and an object of my improvements is to provide latching means with a yieldable automatically acting catch for convenient operation.

Another object of my improvements is to construct and mount the latch and catch respectively upon a gate and post as usually installed in metal barn equipment with partitioning means or fences, and arranged as to be inoperable by animals thereby confined.

These objects I have accomplished by the means which are hereinafter described and claimed, and which are illustrated in the accompanying drawing, in which Fig. 1 is an elevation of a metallic fence or barn inclosure having a gateway in which besides the usual end posts is swingingly mounted a gate provided with latching means for cooperation with an automatically acting catch on the head post. Figs. 2 to 4 inclusive are enlarged details of my invention, with parts removed or sectioned away, Fig. 2 being an elevation of the swinging hasp or latch bar on the gate as engaged with the improved catch on the head post; Fig. 3 being a top plan of the same, and Fig. 4 being a side elevation of the weighted swinging catch only.

The numerals 1 and 2 denote the rear and head posts respectively of a gateway in a metallic fence or inclosure, but I do not limit myself to any particular type thereof. The metal gate 3 is supported to swing to and fro horizontally on the hinge elements or brackets 4 pivoted on the rear stile 5 and fixed on the rear post 1. Upon the middle vertical bar of the gate is fastened the bearing member 7 which is spaced to receive an end of a latch-bar 8 pivoted thereto to swing vertically, the bar extending thence across the forward part of the gate through another bearing member or keeper 10 and projecting beyond the gate to cross the head post 2 when the gate is closed. The latch bar has on its outer face a spaced hand loop 9 for manual use in opening or closing the gate. The outer or free end of the latch bar 8 has a longitudinal slot 11 over a split sleeve 13 mounted on the post 2, and the loop 10 in 50 closes the latch bar 8, limiting its swing.

The split sleeve 13 on the head post 2 has a pair of spaced outwardly divergent ears 14, with inclined edges and apertured to receive a pintle bolt 15 therethrough across their interspace and on which is suspended at its bearing aperture 18 a catch 16 having a finger piece 17 and below on arms 19 a transversely spaced pair of like discoidal weights 20, positioned at opposite sides of the post 2 out of contact therewith to swing freely and by the weights 20 the angular catch 16 is normally engaged over the lower edge of the slot 11 in the latch bar 8, when the gate is closed.

It will be seen that the operator may release the latch bar 8 easily by first pressing down upon the finger projection 17 of the catch 16 to disengage the latter, and then lift the bar by its looped part 9. In closing the gate, the gate is swung toward the head post 2 so that the latch bar 8, being first raised by use of the finger loop 9, may ride upwardly along the inclined edges of the ears 14 and then drop down behind them in notches therein far enough for the angular catch 16 to engage in the slot 11, and be held there by the weighted disks 20 which embrace the post below the bar 8.

A cow or other animal cannot poke down the finger piece 17 as it is inclosed between the narrowly spaced ears 14, and also cannot swing the weights 20 as they are close to the post and the adjacent gate stile 6.

This gate securing means is particularly useful in barn equipment inclosures for pens or compartments or otherwise, and is of inexpensive construction.

Having described my invention, what I claim as new, and desire to secure by Letters Patent, is:

1. The combination with a swinging gate and a head post, of a latch bar pivoted at one end on the gate to project therebeyond across the head post, a medially dentated yoke embracing said post with end weights substantially below its detent and pivotally mounted on the head post to engage said latch bar, to have the detent normally yieldingly keep said detent engaged with the latch bar, and means on said head post at opposite sides of

said detent and extending therebeyond to serve as side guards therefor.

2. The combination with a swinging gate and a head post, of a latch bar pivoted at one end on the gate to project therebeyond across the head post, a split sleeve fastened upon the post therearound with terminal spaced-apart outwardly projecting parts, a catch positioned between said parts and pivoted there-
10 to to engage said latch bar, and divergent arms depending from said catch to loosely embrace the post and having a weight on each tending to yieldingly hold the catch in engagement with the latch bar.
- 15 3. The combination with a swinging gate and a head post, of a latch bar pivoted at one end on the gate to project therebeyond across the post, a catch pivotally mounted on the post to engage the latch bar, spaced ears fixed
20 on the post at opposite sides thereof as guards for the catch, and a pair of depending yoked weights on the catch embracing loosely the post to normally yieldably retain the catch in engagement with the latch bar when the
25 weights are in their lowermost position.
4. The combination with a swinging gate and a head post, of a latch bar pivoted at one end on the gate to project therebeyond across the post and have a terminal slot in
30 its free end, a looped keeper on the gate embracing the latch bar to restrict its scope of swinging movements. A split sleeve fastened on the head post having a pair of spaced divergent apertured ears turned outwardly
35 and with inclined upper edges, a catch having a pintle pivoted in the apertures of said ears and adapted to engage in the slot of the latch bar to lock the latter to the post, and divergent arms depending rigidly from
40 said catch having discoidal terminals embracing the post loosely to normally keep the catch in engagement with the latch bar.

In testimony whereof I affix my signature.

JOSEPH B. CLAY.
